BED CONSTRUCTION

David R. Roth, South Euclid, and Bert T. Smith, Cleveland, Ohio; said Smith assignor to said Roth

Application June 13, 1955, Serial No. 514,987

5 Claims. (Cl. 5—131)

This invention relates to beds and particularly to the frames thereof, the beds being of the Hollywood type so-called wherein head boards of various sizes and types may be used with the same basic frame elements.

More particularly the invention is directed toward the provision of novel clamping means, availed of to fasten and maintain portions of the frame in fixed relation and connect the head board permanently or removably therewith.

Another feature of the invention is the provision of the novel devices as mentioned above which enable adjustment of the various parts as well as fastening the same, the adjustment being simply accomplished and without damaging the head board as heretofore, or requiring a skilled mechanic to carry out the required manipulation.

It is therefore a principal object of the invention to provide novel adjustable clamping or gripping devices to engage transverse frame members and make possible easy positioning of side rails, whereby springs or mattresses of varying widths may be used.

A further object of the invention is to provide devices as above mentioned which are readily manipulated to accommodate varying sizes of head boards, the head boards being in turn fastened to the side rails.

Yet another object of the invention is to provide novel clamping devices on the side rails which will grip and maintain a head board in position after the transverse rails have been adjusted, said head board being removable if desired since the clamping devices do not require screw fastenings or other types of conventional connection or which would leave permanent marks thereon such as bolts and the like.

A still further object of the invention is to provide the clamping devices just above described, which are constructed to provide a bracing effect in use and thus stiffen and in reality strengthen the frame as a whole, there being little or no tendency for the devices to loosen after a time. If in fact such loosening takes place, simple manipulation by the ordinary user may be resorted to and the desired rigidity restored.

Another object of the invention is to provide clamping devices as above described which are themselves of novel form and may be constructed so as to be not only unobtrusive in appearance but be made of inexpensive material in simple shape.

Other and further objects of the invention will be understood from a consideration of the specification appended hereto and set forth in conjunction with a description relating to the drawings wherein:

Figure 1 is a fragmentary view in elevation showing one form of the clamping devices used to connect the head board to the frame.

Figure 2 is a view taken about on the line 2—2 of Figure 1 looking in the direction of the arrows.

Figure 3 is a fragmentary sectional view taken about on the line 3—3 of Figure 1 looking in the direction of the arrows.

2

Figure 4 is a top plan view on reduced scale and somewhat fragmentary, illustrating the general arrangement of a bed frame which involves the clamping devices of this invention.

5 Figure 5 is an end view of a bed frame showing the head board in place and gripped by the clamping members.

Figure 6 is a fragmentary view in elevation, illustrating 10 a further form of clamping device and taken about on the line 6—6 of Figure 4 looking in the direction of the arrows.

Figure 7 is a sectional view taken about on the line 7—7 of Figure 6.

Figure 8 is a fragmentary sectional view showing one 15 of the clamping devices in place and in clamping position, taken about on the line 8—8 of Figure 4 looking in the direction of the arrows.

Referring now to the drawings and initially to Figures 4 and 5 in order to describe generally the type of bed 20 to which this invention is directed, it will be seen that in Figure 4, the usual Hollywood bed frame is provided as far as certain elements are concerned, these elements comprising the parallel side rails indicated at 1 and 2 and the side rail 1 being equipped with a pair of transverse rails 3 and 4, of somewhat more than half the maximum span of the bed, these transverse rails 3 and 4 being connected in each case as by means of the rivet connections 5 for example. As will be readily understood and is well known, the side rails and in fact all of the rails 25 thus far described, are of the usual angle iron type, somewhat more clearly seen in the Figure 3 disclosure for example.

It should be readily understood that the transverse rail members 3 and 4 are connected as seen in Figure 1, 35 these transverse rails being equipped with the leg members 7 and 8, the said leg members 7 and 8 being likewise formed of the usual angle iron part suitably fastened to the transverse rails 3 and 4 in any preferred manner.

Extending from the other side rail 2, are mating rails 40 9 and 10, being of similar shape and length to the rails 3 and 4 previously described, and being likewise fastened as by means of the rivets 11 for purposes well understood in the art, namely that of enabling the respective parts to be folded into position so as to lie in parallelism with the side rail 2, this also being true of the members 3 and 4 with respect to the side rail 1 previously mentioned.

It will also be understood that the transverse rail members 9 and 10 are equipped with the legs 13 and 14 respectively, the said legs corresponding to the legs 7 and 8 previously referred to and likewise being fastened to the transverse rails 9 and 10 in the same manner or in any preferred manner so as to be rigidly engaged therewith.

Turning now to a consideration of Figure 8 in conjunction with the description of Figures 4 and 5, one of the clamping devices or means to which this invention is directed is shown as comprising a V-shaped member 15 having the legs 16 and 17 at right angles substantially, said legs 16 and 17 being equipped furthermore with inwardly directed end portions 18 and 19 respectively. It 55 will be noted that the member 15 is a one-piece member and is formed in any well known working manner of a single relatively thin piece of steel for example, same being of only sufficient width to perform its clamping function.

The legs 16 and 17 of the member 15 are so proportioned as illustrated particularly in Figure 8 as to enable the member to be positioned so as to have or partly encircle there within the angle members 3 and 9, these 60 members comprising corresponding transverse rail members of the opposite side rails 1 and 2 as will be apparent from a consideration of Figure 4.

With the rails 3 and 9 positioned as shown in Figure 8, and further the clamping member 15 emplaced thereon, the set-screw 20 provided and suitably entered and operating in a threaded opening 21, may be manipulated by hand so as to cause the said members 3 and 9 to be inter-engaged and rigidly so along a substantial portion of their respective lengths thus, it will be seen that the member 3 is forced at its edges into an engagement with the inturned ends 18 and 19 of the member 15, and the member 9 is inter-engaged with the leg 16 of the member 15, the set screw 20 bearing against the other leg of the said member 9. This provides a rigid locked reinforced connection which not only prevents slipping or maladjustment of the rails, but likewise provides for a certain amount of spacing within wide limits of the rails 1 and 2 so as to suitably support or provide support for the head board 24 and its connection with the side rails as is now to be described.

It should be noted first of all that two forms of the clamping devices now to be described are shown in the drawings, either of the same being equally efficacious and suitably arranged so as to not only rigidify the entire structure but so as to inter-engage with and lock in place the head board without resorting to the usual screw or nut and bolt fastenings therefore.

With the foregoing in mind the head board 24 of the usual shape and comprising a transverse member 25 suitably fastened at its end to the legs 26 and 27, the said legs 26 and 27 being square or rectangular as the case may be, the board 25 being of any preferred length. Each of the rails 1 and 2 is provided with similar sort of clamping member at its end and therefore only one will be described in conjunction with Figures 1, 2, and 3 as well as 4, so as to particularly point out the novel construction thereof.

Reverting now to Figure 2, it will be seen that the rail 1 for example is provided with a vertical angle member 28, welded or otherwise secured at right angles to the member 1, so as to extend below the same as shown in Figure 1. The angle member 28 is intended to provide a seat against which the rail 27 for example may be located, and in this condition thereagainst, in conjunction with the operation of the clamping member now to be specifically set forth. The clamping member which is denoted 30, is a U shaped member including a connecting leg 31 and the head board leg engaging portion 32 with screw receiving section 33 all of the same being formed of a single member and U-shaped as will be apparent. The leg 33 of the U-shaped member 30 is provided with a suitable set screw of the thumb screw type indicated at 34, suitably engaged with the portion 33 previously mentioned. The member 30 is further arranged so as to be received in a suitable slot seen best in Figure 3 and indicated at 35, said slot 35 being formed or pierced in the seat member 28 previously mentioned likewise.

The member 30 is so arranged with respect to the slot 35 and in fact the slot 35 is so formed in the member 28 that the end portion 33 of the member 30 will engage with the under part 1a of the rail member 1, and when thoroughly tightened up by means of the set screw so as to draw the portion 32 into engagement with the leg 27, a bearing face is provided by the under section 1a previously referred to, this being best illustrated in Figure 1. Therefore when any tendency of the leg 27 is noted as being in a direction such as illustrated by the arrow A, pressure will be exerted on the part 32 and thence against the bearing plate 28, and in turn to the under surfaces 1a of the rail 1. Conversely when pressure is exerted in the direction of the arrow B on the leg 27, the bearing plate 28 will withstand the same in conjunction with the part 30 and thumb screw as controlled thereby.

It should be understood that the other leg 26 of the board 24, is suitably mounted in a similar type of clamp-

ing arrangement, the corresponding parts bearing the same numbers since they are the same shape and corresponding size.

In view of the above it will be readily seen that by positioning the head board at any certain place, the members including parts 30 on the ends of the rails 1 and 2 may be brought into engagement and the thumb screws tightened so as to position the board with regard thereto and thereafter the clamping device 15 having been previously emplaced is tightened on the transverse rails 3 and 9 and 4 and 10, to thereafter enable the same to be drawn up by the thumb screws provided and rigidly unite the entire unit, without resorting to any of the usual fastening devices as previously stated.

Referring now to the other form of clamping device which may be used in place of the device 30 of Figures 1 to 3 inclusive, there is shown in Figures 5 to 7 inclusive a similar arrangement, involving the clamping member generally designated 40, the same being of U-shaped configuration in plan and involving the provision of a connecting web 41 integral with a leg or extension 42 and a further portion 43 the entire unit being U-shaped as was the unit 30 previously described.

The ends of the rails 1 and 2, in this case the rail 2 being illustrated, may be similarly provided with bearing plates 44 fastened so as to be vertically related to the rail 2, the clamping member 40 being mounted below the rail 2 and adapted to bear at its portion 42 against the section of face 2a of the said rail. In order to maintain the member 40 in place, the bearing plate or angle member 44 is equipped with a rivet such as 46, the said rivet passing through a slot 41 formed in the member 40. In this particular case it will be noted that the bearing plate or angle member 44 is reversed as respects the end of the rail 2 so as to partly encircle or enclose the member 26, thus being provided a more rigid bearing than might otherwise be possible.

In any event, it will be apparent that by adjusting the set screw 49 provided, same being mounted in a suitable threaded opening 50 of the portion 42 of the member 40, the part 43 will be brought into engagement with the face of the post 26 and in conjunction with the bearing member 44 rigidly maintain the head rail in place.

In as much as the general arrangement of the parts of the views illustrated in Figures 5 to 7 inclusive serves the same purpose as is true with the parts in Figures 1 to 3 inclusive, no further description of the same is deemed necessary.

In any event, it will be seen that a novel arrangement for such frames is provided whereby the same may be entirely assembled without resort to the usual or common fastening means such as screws or bolts, and that wide variation in adjustment is possible so as to adapt the basic unit to fit any preferred lengths of head rail is made possible. Further by means of the novel forms of clamping members provided, a rigid unit is furnished in the final assembly thereof, and any person of ordinary skill may assemble the same.

We claim:

1. In a bedframe of the class described, in combination, a headboard, a pair of side rails, a pair of transverse rails extending from each side rail, the transverse rails extending from one side rail being positioned so as to overlap those of the other, a first pair of L-shaped clamping members having inwardly extending sections partially surrounding the transverse rails, each having an adjustable device to cause said members to grip said rails, and a second pair of clamping members, one mounted at each corresponding end of a side rail, each of said second pair of clamping members being U-shaped and including a portion engaging said headboard, and other portions engaging the side rail providing the mounting therefor, and adjustable parts for effecting gripping action of said members with the headboard aforesaid.

2. The combination as claimed in claim 1, wherein

each of the second pair of clamping members includes a generally U-shaped body, one of the arms of said body being adapted to engage a surface of the headboard, and the other arm of said body having a set screw threadedly engaged therewith, said arm likewise engaging its corresponding side rail, corresponding ends of the side rails having bearing plates thereon, against which the headboard is positioned by the arms mentioned.

3. The combination as claimed in claim 2, wherein the bearing plates are arranged to enable the headboard to 10 be positioned thereagainst and likewise to act as fulcrums for the set screws mentioned.

4. The combination as claimed in claim 1, wherein each of the first pair of clamping members comprise a substantially L-shaped body, an inturned flange at each 15 extremity and a set screw threadedly engaged in one of the legs of said body.

5. In a bed frame of the class described, in combination, a headboard, transverse and side rails, each side rail having a bearing plate at an end thereof, each said 20

bearing plate being seated against a part of the headboard, a clamping member engaged with each bearing plate and formed so as to clampingly engage such headboard part, each said member bearing against a side rail to limit movement of such member, and instrumentalities co-acting with each said member and its corresponding plate to maintain such member in fixed relation to the headboard part and in bearing contact with the side rail adjacent thereto.
